CABLE FOR COMMUNICATION CIRCUITS

Ernst Fischer, Berlin-Lichterfelde-West, Germany, assignor to Siemens-Schuckertwerke Aktiengesellschaft, Berlin-Siemensstadt, Germany, a corporation of Germany

Application July 21, 1930, Serial No. 469,418, and
in Germany July 27, 1929

3 Claims. (Cl. 173—81)

My invention relates to cables for communication circuits, hereafter called communication cables, and specifically to cables of that kind in which shields situated in the interior of the cable

5 core are continuously grounded.

For the purpose of grounding the metallic sheaths or envelopes arranged inside the core of communication cables to shield individual speaking circuits or groups of speaking circuits, hitherto, nettle-cloth tapes were generally used which are interwoven with thin metal wires. Such tapes, however, have the disadvantage that often when they are being applied to the cable core or when the cable is bent, some of the wires break owing to the pull exerted upon the thin wires, and that for this reason a continuous grounding is not possible. There is the further danger of the broken wires puncturing the insulation of the wires and causing cable faults.

20 According to the invention, these disadvantages are avoided by employing the well-known metallized tapes to ground the shields but in such a manner as to ensure a continuous reliable grounding along the whole length of the cable. Preferably two tapes are used for this purpose, one of which is turned with its metallic side towards the speaking circuits, i. e., toward the metallic envelopes or shields, whereas the metallic side of the other tape is turned outwardly toward the lead sheathing. The two tapes are wound spirally round the bundles of speaking circuits, or the cable core in such a manner that their metallic sides are in contact with each other over a certain tape breadth. When using only one tape it is also possible to obtain a sure, continuous grounding by folding the tape before it is wound round the core of a cable in such a manner that a part of the metallized side lies towards the core, while the other part of the metallized side is turned outwardly

40 toward the lead sheathing. Another possibility is to apply, for example by means of a double spinning machine, alternately an insulating and a conducting tape of tin-foil or the like in such a manner that half of the one tape overlaps half of the other; or a conducting layer may be folded round one edge of an insulating tape and the tape wound in such a manner that the conducting layer makes a good contact both with the lead sheathing and with the metallic sheaths round the speaking circuits or group of speaking circuits. In many cases it is sufficient to place separate metallic strips between the insulating tapes in such a manner that said strips form a good electrical connection between the metallic envelopes in

the interior of the cable core and the lead sheathing.

My invention is illustrated in the accompanying drawing in which

Fig. 1 represents a view, partly in longitudinal section of one modification,

Fig. 2 represents a transverse section of the cable on line 2—2, Fig. 1;

Fig. 3 represents a second modification, partly in full view, partly in section, and

Fig. 4 represents a transverse section of the cable on line 4—4, Fig. 3.

Fig. 1 shows a cable core 2, metallically shielded at 5, and to which two metallized paper tapes 3 and 4 are, according to the invention, applied in such a manner that the metallized side of tape 3, indicated by a thickened line in the sectioned portion, lies against the metallic shield 5, whilst the metallized side of tape 4, also indicated by a thickened line in the sectioned portion, lies partly against the metallic side of the tape 3 and partly against the outer lead sheathing 6. In the full view portions of Fig. 1 the metallized sides of the tapes are stippled.

The cable core 2 consists of a plurality of groups of conductors, each group of which consists of a conventional plurality of conductors, such as quads 15, 16 and 17. In Fig. 1 not all quads are visible. Each quad of insulated conductors may be wrapped as shown at 14, in any conventional manner, which forms no part of the present invention. The quads are surrounded by a metallic shield 5 which thus is in contact with the wrappings 14 of the quads. Thus it will be seen from the foregoing, that in case the wrappings 14 are provided with a shielding, which is the conventional construction in such cables, the individual quad shieldings become conductively connected through shielding 5 by way of the metallized tape insulations 3, 4 to the outer cable sheathing 6.

In Figs. 3 and 4 a modification of such a wrapping is illustrated in connection with a cable, whose core 2 may likewise consist of a plurality of conventionally constructed groups of conductors 15, 16, 17. All the groups are surrounded by a common shield 12 which connects any individual shieldings of the wrappings 14 of the groups, but in this case the outer metallized tape winding consists of a single tape 13 which is applied to the metallic core shield 12. In order to establish a metallic connection between the core shield 12 and the outer sheathing 6, this tape 13 is folded partly back on itself in longitudinal direction, as shown in Fig. 3, in such a manner that a part

of its metallized side, also indicated by a thickened line in the sectioned portion of Fig. 3, and stippled in the full view portion, lies against the core shield 12, and the remaining part of the 5 metallized side faces outwardly, so that it comes to lie against the cable lead sheathing 6 when the latter is applied to the cable.

I claim as my invention:—

1. In a cable of the character described, in 10 combination with a core containing a plurality of groups of insulated conductors, a metallic shielding for said groups and a common outer metallic cable sheathing for said groups, of an overlapping insulating tape winding arranged in 15 superposed layers and enveloping said shielded groups, the tape, of which said winding is composed, being metallized on one face only, the metallized face of the innermost layer being in electrical contact with the metallic shielding of said 20 individual conductor groups, the metallized face of the outermost layer contacting with said outer metallic cable sheathing, and the metallized face of each layer contacting with the metallized face of its adjacent layer, to electrically connect the 25 group shielding with said outer cable sheathing.

2. In a cable of the character described, in combination with a core containing a plurality of groups of insulated conductors, a metallic shielding for said conductor groups and an outer

30

common metallic cable sheathing for said groups, of an overlapping winding of two non-conducting tapes enveloping all of said groups, said tapes being metallized on one side only and facing one another with their metallized sides, and being wound to only partly overlap one another, so that one part of the metallized side of one winding electrically contacts with the group shielding and one part of the metallized side of the other winding contacts with said cable sheathing, whereby a continuous metallic contact is established between said group shielding and said cable sheathing.

80

3. In a cable of the character described, in combination with a core containing a plurality of groups of insulated conductors, a metallic shielding for said conductor groups and an outer common metallic cable sheathing for said groups, of an overlapping winding of one non-conducting tape, metallized on one side only and being folded lengthwise partly back on itself with the metallized side outside, and being wound to envelop said shielded groups with the non-folded portion of one turn overlapping the folded portion of the preceding turn, whereby the metallized side 95 of said tape establishes a continuous metallic contact between said group shielding and said cable sheathing.
